UNITED STATES PATENT OFFICE.

ALVA UDELL, OF TORONTO, ONTARIO, CANADA.

POSTAL CABINET.

SPECIFICATION forming part of Letters Patent No. 431,679, dated July 8, 1890.

Application filed November 20, 1889. Serial No. 331,046. (No model.)

To all whom it may concern:

Be it known that I, ALVA UDELL, a citizen of the United States, residing in the city of Toronto, Dominion of Canada, have invented 5 a new and useful postal device for the reception and safe keeping of letters, papers, and other articles, where only the owner or the person to whom the same are addressed can have access thereto, of which postal device 10 the following is a specification.

The object of my invention is to provide a postal cabinet having lock-boxes and lock-drawers, which shall be more convenient and afford more facilities for public business than 15 the rigid walls and partitions holding the post-office boxes in common use.

Heretofore in post-offices the lock-boxes have been retired into the walls or partitions of the post-office building, which wall or partition 20 is accessible by the public only from one side, thereby occupying a great amount of space in proportion to the desired number of boxes and obstructing the free passage of light so necessary in a post-office building. 25 To obtain more light and additional box room the walls and partitions of the buildings or compartments heretofore commonly used for post-office purposes have been arranged in nearly all possible forms of construction, but resulting in little or no advantage over the straight and common wall. To obviate these difficulties in a simple and effective manner I have devised a postal cabinet having lock-boxes or lock-drawers in a 30 revolving wall, and designed to be used in all public and private buildings and on street-thoroughfares for the reception and safe deposit of letters, papers, and other mail or express matter in the course of distribution.

35 I have also devised certain new and novel improvements useful in my postal cabinet, whereby it may be used to safely keep and display small articles of merchandise, and also as a postal device commanding public 40 attention and use to afford facilities as a building, block, or street directory for circulating business-cards and to display and facilitate distribution of railway, steamship, and other advertisements. I attain these objects by the mechanism illustrated in the accompanying drawings, in which—

Figure 1 represents an exterior elevation of my postal device or cabinet. Fig. 2 is a vertical section representing a pivotal floor-stand embodied in my invention. Fig. 3 is a 55 top plan. Fig. 4 is a vertical section.

Similar letters refer to similar parts throughout the several views.

A indicates a metallic flange or stool, from the center of which vertically extends upward 60 the pivotal axis B, upon which, if desired, the postal cabinet may or may not be made to revolve while standing upon a counter, table, bench, wall, post, block, suspended swing, swinging crane, or other holding device 65 adopted by the person employing my invention.

Y indicates a metallic floor-stand or spider having casters w, and provided with the pivotal axis B, upon which the postal cabinet 70 may be adjusted when desired to be conveniently moved about a room.

The metallic flange C and cylindrical box D encircle the pivotal axis B. The metallic flange C and cylindrical box D are constructed 75 rigidly together, both being cast of metal in the same mold.

E indicates the main floor of the postal cabinet, and F represents the extension-floor 80 of the cabinet. The extension-floor is rigidly attached to the lower surface of the main floor by means of screws, bolts, or glue, as best meets the choice of the constructor. Through the center of the main floor is adjusted the cylindrical box D, which extends 85 upward above the main floor to a point in height equal to about two-thirds the height of the cabinet above the metallic flange A. The lower surface of the main floor is by screws or bolts rigidly attached to the upper 90 surface of the metallic flange C. The upper end of the cylindrical box D is completely closed and rests upon the pivotal axis-point a, and upon which point the body of the cabinet rests its weight while revolving upon its 95 perpendicular axis, thereby obviating frictional bearings upon the flange A, where the cylindrical box D would rest upon the same. To avoid unnecessary friction between the contiguous surfaces of the cylindrical box D 100 and the pivotal axis B, the diameter of the inside surface of the cylindrical box is en-

larged nearly its entire length, as shown by the space represented by *b*, Figs. 2 and 4. To avoid unnecessary weight of metal, the pivotal axis *B* and its cabinet floor-stand *Y* 5 are constructed hollow throughout almost their entire length and dimensions, as indicated by *c* and *x* in Fig. 2.

G indicates a series of lock-boxes or lock-drawers, each divided into two compartments 10 *H* and *I* by an intervening floor *J*. The front or outside walls *d* of said lock-boxes are constructed principally of metallic doors and frames, and the rear inside walls *e* are made of wood and glass similar in thickness and 15 quality to that usually used in the construction of post-office pigeon-holes. The partition-walls *f*, also the main intermediate floor *K* and intervening floors *j*, of the lock-boxes are constructed of wood similar in 20 quality and thickness to that usually used for such purpose in the construction of post-office lock-boxes.

Each lock-box is designed to keep safely 25 small articles of merchandise—such as cigars, cigarettes, &c.—and for the safe deposit of letters, cards, papers, and other mail or express matter in the course of distribution.

The mail and express matter is deposited 30 in each lock-box by passing it through a drop-plate opening *g* in door *L*. Each drop-plate opening *g* is large enough to admit the larger packages, such as papers and other similar articles. Therefore it must of necessity be 35 large enough to admit the fingers of a small hand. The front end of each intervening floor *j* is displaced by a small metallic bar *h*, having a slot or opening *i* therein long enough and large enough to admit letters, but too small to admit the fingers of the hand. The 40 opening or slot *i* in the metallic bar *h* is constructed on a direct inclined plane with the drop-plate opening *g*, and through both letters can be easily passed into the lower compartment *I* by raising the drop-plate *j*, either with 45 the letter or by a separate hand, thus placing the letter beyond the possible reach of any person inclined to theft. Papers or similar articles which cannot be passed through the opening or slot *i* are deposited in the compartment *H*. On opening the door *G* ample access is afforded to both compartments of 50 the lock-box. The lower compartment *I* of each lock-box is large enough to hold a cigar-box of the size in usual use, thus enabling a 55 person to have his private box of cigars and mail-matter safely kept awaiting his convenience.

The main front walls of my postal cabinet are constructed of a circular series of vertical 60 frames attached rigidly to the front end of the partitions and floors of the lock-boxes by means of lugs and screws or rivets. To each frame so adjusted in front of a lock-box is, by 65 hinges *k*, attached a lock-box door *L*. Each intervening frame *N*, adjusted in front of the triangular-shaped boxes *M*, extends vertically and forms a frame fronting three of the boxes

M. The frame is so constructed that in front of each box *M* it forms a card-holder *O*, which may be of any desired pattern or construction 70 adopted by the person employing my invention. In each card-holder a number of cards of the same size and weight are placed facing outwardly, and on the faced side are printed advertisements, photographs, or other desired 75 characters, the front card of which exposes the same to view for an indefinite period of time.

Each lock-box door *L* is provided with a drop-plate *j*, a drop-plate opening *g*, a lock *p*, 80 and transparent panel *q*.

Between the lower series of the outside wall frames *N* and the extension-floor *F* are adjusted the rear ends of the show-case frames *r*, rigidly attached by means of lugs and 85 screws or rivets to the extension-floor *F*, also to the partition-walls *f*, which are continued downward for that purpose. Each show-case frame *r* is constructed of metal, preferably of brass, and is rigidly attached to the lower 90 front surface of the extension-floor *F* by means of screws or rivets passing through the lugs *s*.

The upper and front surfaces of the show-cases *T* are constructed of transparent glass 95 adjusted and secured to the show-case frames by means of putty or any other device therefor chosen by the constructor. Within each show-case *T* may be adjusted a cigar-tray *U* 100 or other display mechanism, which, with contents, can be removed or displaced at pleasure by opening lock-box door *L*, raising drop-door *W*, and passing the tray or similar device backward through the rear end of the show-case frame *r*, and thence upward and outward through the passage-ways thus opened. 105

Cigar-trays or similar devices and contents placed in the show-cases *T* fronting the card-holders *O* can be removed or displaced at pleasure by passing them sidewise within the show-case frames *r* to a position fronting a 110 lock-box door, and thence backward, upward, and outward through the passage-ways above described. A price-mark or other card or advertisement may be placed within each show-case, occupying the space (represented by *t*) 115 provided therefor, and be removed or displaced at pleasure by the method above explained. The show-cases *T* thus constructed and arranged afford an excellent method of exhibiting jewelry, cigars, medicines, valuable 120 toys, or other similar articles.

The crown-molding *u* consists of a series of metallic frames *v*, inclining forward and encircling the upper main floor of the cabinet, and are rigidly attached to the upper main 125 surface of such floor by means of screws or rivets passing through metallic lugs. The crown-molding frames *v* are constructed, preferably, of cast-brass, and within each frame is adjusted and secured a plate of polished glass, 130 preferably mirror, with advertisements ground therein. Behind the crown-molding frames and against the rear surfaces thereof, inclined forward for such purposes, may be placed

steamship or railway folders or other advertisements, having their front surfaces exposed to view above the crown-molding, and within easy reach of an adult person. Such folders or advertisements are held securely in a normal position by means of pockets, stop-wires, or other devices arranged therefor, as best meets the choice of the person employing my invention.

10 While I have shown my invention constructed in part of metal, wood, and glass, I do not limit myself to the dimensions or material named in the construction of any part thereof.

15 What I claim as my invention, and desire to secure by Letters Patent, is—

1. A rotary postal cabinet having lock-boxes or lock-drawers in its revolving wall for the reception and safe deposit of articles of merchandise, or letters, papers, or other mail or express matter in the course of distribution.

20 2. In a postal-cabinet having lock-boxes or lock-drawers, the card-holders used for the purpose of displaying, distributing, or circu-

lating cards or advertisements, substantially 25 as set forth.

3. In a postal cabinet having lock-boxes or lock-drawers, the show-cases used for the purpose of displaying or exhibiting merchandise, substantially as set forth.

4. In a postal cabinet having lock-boxes or lock-drawers, the floor-stand Y, with pivotal axis B, constructed and adjusted substantially as set forth.

5. In the construction of a postal cabinet 35 having lock-boxes or lock-drawers, doors L, frames N, boxes G, compartments H and I, crown-molding u, show-cases T, tray U, drop-door W, drop-plate j, metallic bar h, intervening floors J, intermediate floors K, and card-holders O, constructed upon flange C, and adjusted around cylindrical box D, substantially 40 as set forth.

ALVA UDELL.
